STORAGE BATTERY TERMINAL

Filed Dec. 26, 1930

Inventor:
Thomas Hill.
by Grover Leffhill,
Attorney.

UNITED STATES PATENT OFFICE

THOMAS HILL, OF DETROIT, MICHIGAN

STORAGE BATTERY TERMINAL

Application filed December 26, 1930. Serial No. 504,793.

This invention has reference to battery terminals and it is my intention primarily to provide a terminal of this character that presents an entirely new origin and purpose, and the outstanding purpose of the invention is the extremely simple method of construction and operation.

My invention is composed of a body having the customary clamping portion adapted to engage the post of the battery, and a sleeve portion integral with this body adapted to engage one end of the electrical circuit cable, and the principal advantage is that the clamping bolt employed remains permanently fixed with the battery post connecting portion of the invention, thus eliminating any possibility of the bolt becoming disengaged therefrom or entirely lost. The operation of the bolt is identical with that of any other type of terminal, thus preventing any difficulty or confusion in its normal use.

The invention possesses further advantages all of which will be brought out during the course of the following detailed description, illustrated within the accompanying drawing, and more fully pointed out in the appended claim.

With reference to the drawing:

Figure 1 is a plan view of the complete invention clearly showing the same normally connected to the battery, the latter being shown in part, as indicated.

Figure 2 is a plan view of the invention with part thereof in section, and the bolt omitted.

Figure 3 is a side elevation of the invention with a portion thereof in section, and with the bolt omitted.

Figure 4 is an elevation of the bolt of the invention.

Figures 5 and 6 show a modified form of my invention in part elevation and sectional views.

The invention comprises a body 1 which is preferably of a suitable cast metal and having formed thereon projecting sleeve portion 2 which is adapted to engage one end of an electrical circuit, as clearly seen in Figure 1. Integral with body 1 is portion 3 which is provided with inner tapering surface 4 to

conform to the post of the battery, and a novel feature of my invention is the plurality of recesses 5 and countersunk upper portion 6 employed as shown in Figures 2 and 3, and the purpose of portions 5 and 6 being to admit of a suitable lubricating paste which is disposed to liquefy upon the application of a slight heat, thus permitting the terminal to turn sufficiently to admit of perfect ease in the removal thereof from the post when desired.

Bolt 7 is provided with reduced shank 8 thereon, and with reference to Figure 2 it is clearly observed that threaded hole 9 is provided and also plain hole 10, and both of the said holes being in perfect alignment. Bolt 7 having similarly threaded portion thereon to engage hole 9 and shank 8 adapted to pass through hole 10 and permitted to freely rotate therein upon the turning of bolt 7 in either direction, and in Figure 1 it is clearly seen that washers 11 are employed and to engage shank 8 of the said bolt, the end of the said shank slightly riveted as at 12, thus it is now understood that when bolt 7 is reversed within threaded hole 9 and the end of the said bolt being operatively retained in portion 13 of the invention portion 3 thereof will be released from the battery post, and likewise the drawing up of the said bolt will draw portion 3 firmly upon the said post. In this manner the terminal is quickly released from the battery and likewise attached with bolt 7 ever available for instant use.

The modified form of my invention as indicated in Figures 5 and 6 embodies a bolt similar to bolt 7, body portion 3, recesses 5 and countersunk portion 6, sleeve portion 2, washers 11, holes 9 and 10.

While I have hereinabove set forth a major form of my invention in a precise embodiment the same is nevertheless susceptible to minor changes in the details of construction during any probable further development of the same for the market, however in this event a departure from the general principle as disclosed would be consistently avoided.

Having thus described my invention, what I claim as new is:

A storage battery terminal of the character described, having a body with a clamping portion formed integral thereon and adapted to engage a battery post, means 5 within the said clamping portion for accommodating a lubricating paste, comprising a plurality of uniformly spaced recesses extending completely through the inner surface

of the said portion and the upper end of the said recesses terminating within a countersunk surface within the upper end of the aforesaid clamping portion of the device.

In testimony whereof I hereunto affix my 70 signature.

THOMAS HILL.
